RAILWAY SWITCH BOX CONNECTION

Herbert L. Bone, Forest Hills, Pa., assignor to
The Union Switch & Signal Company, Swiss-
vale, Pa., a corporation of Pennsylvania

Application October 24, 1936, Serial No. 107,494

1 Claim. (Cl. 287—90)

My invention relates to railway switch box connections that are used to connect switch boxes with railway switch points. Specifically, my invention relates to novel and improved connecting mechanisms that are utilized to connect a switch point and a switch box to a connecting rod.

As is well understood in the art, it is customary, in connection with signaling and interlocking systems, to employ switch boxes, connected to the track switches, for the purpose of detecting in any suitable manner the position of the switch point with respect to the associated track rail. It is ordinarily desirable that the switch box should register the movement of the switch point through a small portion of its range but any lost motion in the connecting mechanism between the switch point and the switch box allows an increase in the range of travel before such travel is registered by the switch box. My invention is designed to provide a form of connecting mechanism in which this lost motion is automatically absorbed as it appears.

It is also desirable that the motion of the switch point, particularly when moving away from the associated track rail, should be transmitted instantly and directly to the switch box since the switch box is relied upon to detect when the switch point is not in proper relationship to the associated track rail for the safe passage of traffic. In the usual form of connecting mechanism for taking up lost motion automatically, resilient means is employed in such a manner that the motion of the switch point when moving away from the associated track rail is transmitted through such means. Consequently, there is a possibility of the switch point moving away from the associated track rail without such movement being registered by the switch box. My invention is designed, not only to take up lost motion automatically, but also to transmit the motion of the switch point, when being moved away from the associated track rail, directly and rigidly to the switch box. That is, the connecting mechanism for absorbing lost motion is employed to transmit motion to the switch box only when the switch point is moved towards the associated track rail.

The present application is a continuation-in-part of my copending application, Serial No. 84,499, filed on June 10, 1936, for Railway switch box connection.

I will describe representative forms of connecting mechanisms embodying my invention, and will then point out the novel features there-
of in the claim.

My invention will best be understood by reference to the accompanying drawing, in which:

Fig. 1 is a top plan fragmentary view of a portion of a railway switch, its supporting tie, a switch box, and connecting means between the switch box and track switch embodying my invention. Fig. 2 is a fragmentary side elevational view of the arrangement shown in Fig. 1 with parts broken away to illustrate more clearly the construction of the connecting means embodying my invention.

Similar reference characters refer to similar parts in each of the two views.

In Fig. 1, the reference character 1 designates an ordinary railway track tie. This tie supports a track rail 2 which has a switch point 3 operating in conjunction therewith. Securely fastened to switch point 3 in any suitable and convenient manner is a switch point lug 4 which is provided with a spherical head 5 at its free end.

The tie 1 also supports an ordinary and well-known switch box 6. This switch box is here shown as of the type having a protruding operating shaft 7 to which is connected an operating crank arm 8. A bolt 9 is fastened in any suitable manner to crank arm 8 such as by a nut 10. The bolt 9 is provided at its free end with a spherical head 11.

In order to connect the head 5 with the head 11, I provide a connecting rod 12 having on each end thereof connecting mechanism of novel construction.

The form of mechanism for connecting rod 12 with head 5 is best shown in Fig. 2. An upturned portion 13 of connecting rod 12 is provided with a concave spherical surface 14 in engagement with the outside surface, with respect to track rail 2, of head 5. Opposite the concave surface 14 and in engagement with the inside surface, with respect to track rail 2, of head 5 is a concave surface 16 of a plunger 17. The plunger 17 fits into a recessed portion 18 of a mating cap 19, and has a tail member 20 encircled by an outer spring 21 and an inner spring 22. One end of each spring bears against plunger 17 and the other end of each spring bears against the bottom of the recessed portion 18 of mating cap 19. The mating cap 19 is fastened to upturned portion 13 of rod 12 by a bolt 23 and a nut 24. The mating cap 19 is provided with a lug 25 which engages with the upturned portion 13 of rod 12 to hold the mating cap in proper alignment with bolt 23 while nut 24 is being tightened up.

It will be noted from Fig. 2 that the portion 18 of the mating cap which houses the plunger 17 and the associated compression springs extends inwardly from the ball-shaped lug head 5 and toward the rail 2 with which the lug-carrying switch point is associated. As compared with past arrangements wherein corresponding parts are extended outwardly from the lug head, this is a feature of practical advantage in that it 10 protects these parts from the possibility of damage due to mechanical contact by dragging equipment of train vehicles which pass along the track. It will also be seen, moreover, that the further feature of employing the upturned portion 15 of the controller rod 12 as half of the ball socket 14-16 likewise provides practical advantages. In particular, it effectively eliminates the possibility of the objectionable lost motion which becomes present with a loosening of the 20 conventional separate rod-end fitting when that fitting is of the usual screw-attached or other equivalent type. Still further, it will be observed that use of the positioning projection 25 on the base portion of the member 19 allows but 25 a single bolt 23 adequately to secure this fitting to the upwardly extending portion of the controller rod.

At the switch box end of the connecting rod, another form of connecting mechanism, as here 30 shown, comprises an adjustable member 26 which is screwed onto a threaded portion 27 of rod 12, and is held in position by a nut 28 and lock washer 29. The member 26 is provided at its free end with a recessed portion 30 enclosing head 11. Disposed in the inner part of recessed 35 portion 30 is a plunger 31 having a concave spherical surface 32 in engagement with the surface of head 11 on the side nearest the track rail. Encircling a tail member 33 of plunger 31 is a spring 34 having one end bearing against the bottom of recessed portion 30 and the other end bearing against the plunger 31. Threaded into the orifice 35 of recessed portion 30 is a member 36 having a concave spherical surface 37 in en-

gagement with the surface of head 11 which is opposite from concave spherical surface 32. For holding the member 36 firmly in position, a key 38 is provided which extends through members 36 and 26. 5

The above described construction is obviously one that will automatically absorb lost motion due to wear of the parts because springs 21, 22, and 34 will hold the connecting surfaces tightly in engagement with each other. Furthermore, 10 the connecting mechanism is such that motion transmitted from the switch point to the switch box, when the switch point is moving away from the rail, will be transmitted directly from head 5 to upturned portion 13 or rod 12, and hence 15 through rod 12 and member 36 to head 11.

Although I have herein shown and described only representative forms of connecting mechanisms embodying my invention, it is understood that various changes and modifications may be 20 made therein within the scope of the appended claim without departing from the spirit and scope of my invention.

Having thus described my invention, what I claim is:

In a ball-and-socket connection, in combination, a first member having a substantially spherical end portion, a second member having therein a concave recess which is adapted to receive one side of said spherical end portion, a cooperating housing body having a cap portion which is adapted to fit over the other side of said spherical end portion and a base portion which includes a positioning extension engageable with a mating portion of said second member, means for removably securing said housing base to said second member, a compression spring disposed within said housing cap, and a plunger urged by said spring against the said other side of the spherical end portion of said first member and provided with a bearing surface which is concavely shaped 35 to receive said member end. 40
